J. T. WATTS.
PAIR OF SUSPENDERS.
FILED MAY 25, 1921.

UNITED STATES PATENT OFFICE.

JOHN T. WATTS, OF LOS ANGELES, CALIFORNIA.

PAIR OF SUSPENDERS.

Application filed May 25, 1921. Serial No. 472,344.

To all whom it may concern:

Be it known that I, JOHN T. WATTS, a citizen of the United States, residing at Los Angeles, in the county of Los Angeles and 5 State of California, have invented a new and useful Pair of Suspenders, of which the following is a specification.

My invention relates to suspenders such as are worn for supporting trousers.

10 The principal object of my invention is to produce an article of the class described of simple form and construction which automatically adjusts itself to the movements of the wearer, provision being made for regulation or adjustment of the shoulder straps with respect to each other.

Referring to the drawings, which are for illustrative purposes only,

Fig. 1 is a view on a reduced scale of a 20 complete pair of suspenders showing an embodiment of a form of my invention, the shoulder straps being folded back upon themselves.

Fig. 2 is a view of the back portion of 25 the suspenders showing the same as worn.

Fig. 3 is an enlarged view of the back of the suspenders.

The suspenders consist of two shoulder straps 11 which are provided at their forward ends with flattened eyes 12 to which are secured in any suitable manner cords 13 which terminate in buttonhole tips 14 by means of which the forward ends of the straps are secured to the trousers, such ends 35 being also provided with any common form of adjusters 15 by means of which the length of the straps may be varied.

The back end of the straps along the inner edge of such straps are provided with a 40 series of perforations or eyes 18 arranged to receive a cord or lace 20, such cord or lace being for the purpose of adjusting the distance between the back ends of the straps.

The lower back end of each strap 11 is 45 provided with a flattened eye 22 to which is pivotally secured by means of a pin or stud 23 an upper guide 24 for a cord 25, each end of such cord 25 being provided with a buttonhole tip 26 by means of which the back of the suspenders are connected to the trousers.

The cord 25 extends through the upper guides 24 and through lower guides 28 which are pivotally mounted on pins or 55 studs 29, such pins 29 being mounted in clasps 30 which are secured to the upper

ends of the tips 26 or directly to the cord at the upper ends of the tips. The cord 25 forms a U-shaped loop, the legs of the loop being formed by the cord slidably extending through the guides 24 and the lower end of the loop being formed by that portion of the cord extending through the lower guides 28.

33 designates a tie strap or band secured 65 at its ends in any suitable manner to the clasps 30, such band having secured to it a clasp 34 which is provided with a guide 35 through which the looped end of the cord 25 slidably extends.

70 Suspenders made as above described permit an adjustment between the straps 11 in the back so that the individual wearer may adjust the distance between the straps so that the same may be comfortably worn, it 75 being understood that the lace or cord 20 may be placed in any set of the eyes 18, that is, either higher or lower on the back as may be desired.

The back adjuster, it is to be understood, 80 that is, the cord 25 is only fixed at its ends and slidably extends through the guides 24 and 28 which arrangement permits the loop formed in the cord being shortened on one side and lengthened on the other, according 85 to the strain or pull of the straps 11.

I claim as my invention:

1. A pair of suspenders comprising a pair of shoulder straps each provided at its front end with garment attaching means; a guide 90 secured to the back end of each strap; a cord slidably extending through said guides; a tip on each end of said cord; a guide on each tip through which said cord slidably extends; a tie band connecting the ends of 95 said cord; and means for adjustably spacing the back ends of said straps apart.

2. A pair of suspenders comprising a pair of shoulder straps; garment attaching means at the front ends of said straps; 100 means for adjusting the back ends of said straps with relation to each other; and an adjuster connected to the back ends of said straps consisting of a cord, garment securing means on each end of said cord, and 105 guide means on said straps and the ends of said cord through which said cord slidably extends to form a U-shaped flexible member.

3. A pair of suspenders comprising a pair of shoulder straps; garment attaching 110 means at the front ends of said straps; means for adjusting the back ends of said

- straps with relation to each other; and an adjuster connected to the back ends of said straps consisting of a cord, garment securing means on each end of said cord, and 5 guide means on said straps and the ends of said cord through which said cord slidably extends to form a U-shaped flexible member, and a tie band between the ends of said cord.
- 10 4. A pair of suspenders comprising a pair of shoulder straps; garment attaching means at the front ends of said straps; said straps having a series of perforations; a

lace extending through said perforations; and an adjuster connected to the back ends 15 of said straps consisting of a cord, garment securing means on each end of said cord, and guide means on said straps and the ends of said cord through which said cord slidably extends to form a U-shaped 20 flexible member, and a tie band between the ends of said cord.

In testimony whereof, I have hereunto set my hand at Los Angeles, California, this 18th day of May, 1921.

JOHN T. WATTS.
